UNITED STATES PATENT OFFICE.

LEOPOLD KABIS, OF CHEYENNE, WYOMING, ADMINISTRATOR OF THOMAS MOORE, DECEASED.

DESIGN FOR A BUCKLE.

SPECIFICATION forming part of Design No. 29,280, dated August 30, 1898.

Application filed July 27, 1898. Serial No. 687,045. Term of patent 14 years.

To all whom it may concern:

Be it known that THOMAS MOORE, deceased, late a citizen of the United States, and a resident of Cheyenne, county of Laramie, and State of Wyoming, duly invented and produced a new and original Design for Buckles, of which the following is a full, clear, and exact description, reference being had to the accompanying drawing, forming a part hereof.

The figure is a plan view of a buckle embodying the design.

As shown in the drawing, the leading or material feature of the design consists of the rectangular skeleton frame 1, the upper horizontal bar 2 of which is somewhat larger in diameter than is the balance of the frame, and arranged at a slight distance above the

enlarged bar 2 is a horizontally-arranged bar 3, the same being somewhat shorter than is said frame 1, and extending downwardly and outwardly from the ends of said bar 3 are the bars 4, the lower ends of which are connected to the upper ends of the rectangular frame 1 by the bars 5.

What is claimed is—

The design for a buckle, substantially as herein shown and described.

In testimony whereof I affix my signature in presence of two witnesses.

LEOPOLD KABIS,
Administrator of Thomas Moore, deceased.

Witnesses:

WALTER R. STOLL,
WM. R. SCHNITGER.
